UNITED STATES PATENT OFFICE.

WILLIAM O. WENTWORTH, OF NEW YORK, N. Y.

ELECTRIC RIVETING DEVICE.

1,403,529.

Specification of Letters Patent. Patented Jan. 17, 1922.

Application filed October 10, 1919. Serial No. 329,760.

To all whom it may concern:

Be it known that I, WILLIAM O. WENTWORTH, a citizen of the United States, residing at New York, in the county of New York and State of New York, have invented certain new and useful Improvements in Electric Riveting Devices, of which the following is a specification, reference being had therein to the accompanying drawing.

- 10 My invention relates to electrically and magnetically operated riveting devices. It is my purpose to provide a device of the character referred to in which the instrumentalities are magnetically held to the work in operative position to the rivet, and the latter heated electrically to the proper temperature to permit its upsetting by an electro-magnetically operated element constituting a component part of the device.
- 15 Other purposes and advantages of my invention are reduction of the number of workmen necessary in a riveting gang, avoidance of burning the rivet in heating with its obvious results, a more efficient joint at the rivet connection, elimination of noise, increase in rapidity with which the rivets may be applied, elimination of strain on the workmen whereby the physical standard required for such work is lowered and the employment of cheaper labor rendered possible, and a material reduction in riveting cost.
- 20
- 25
- 30

I will describe my invention in the best form known to me at present and wherein I employ a movable solenoid core as the means for the upsetting of a heated rivet, but it should be understood that my invention is susceptible to changes in proportion and arrangement and to desirable additions with the exercise of only ordinary mechanical skill and without departing from the scope of my invention.

In the drawings chosen to illustrate my invention, the scope whereof is pointed out in the claims—

- 45 Figures 1, 2, 3 and 4 are views illustrating successive steps in the use of my device;
- 50 Fig. 5, a detail view of the advance end of the retarding bar of the dolly bar element of the device showing the heating circuit terminal carried thereby which is adapted to engage one end of the rivet;

Fig. 6, a detail view of the advance end of the solenoid core of the riveting or upsetting element of my device and showing the terminal of the heating circuit which engages the other end of the rivet;

Fig. 7, a detail view of a preferred construction of leg terminal for use in connection with both the dolly bar element and the riveting element of the device; 60

Fig. 8, a diagrammatic view of the circuits which are controlled by the switches carried by the handle of the dolly bar element.

Fig. 9, a similar view in respect to the riveting element and the switches carried thereby; and

Fig. 10, a diagrammatic view illustrative of the circuits employed in the use of the device. 70

The dolly bar element of my riveting device is indicated at A and the riveting or upsetting element at B. The former is substantially U-shaped to form the legs or arms 10 and 11 which constitute the cores of magnets whose windings are indicated at 12 and 13 respectively. The arm connecting portion of the dolly bar element A is provided with passages 13' and 14, through which the windings 12 and 13 are led from a suitable source of electric supply controlled through the medium of switches carried by the dolly bar element and to be hereinafter referred to. The element A also includes a central retarding bar or buffer 15 which is recessed 85 at its outer end to receive the head of the rivet to be upset, said recess being indicated at 16. The base of this recess 16 is further recessed at 17 and confined within the latter and insulated from the bar 15 is an electrical 90 heating circuit terminal 18 of copper or other low resistance material. Connected with this terminal 18 and extending laterally through the bar 15 and insulated therefrom is a binding post 19 whereby the 95 terminal 18 may be conveniently connected to a conductor of the heating circuit, such conductor being led through the passage 14. The outer ends of the arms 10 and 11 are provided with engaging feet 20 which have 100 a rotatable bearing connection 21 with said arms whereby the feet may readily adjust themselves to the surface with which they are engaged. If desirable the engaging faces of the feet 20 can be curved as shown 105 at 22 in Fig. 7 and this for the purpose of increasing the traction between said feet and the metal plates being riveted. The shape of the apparatus may be varied for convenience in corner work. 110

The riveting or upsetting element of my device is also substantially U-shaped and in-

cludes arms 23 and 24 forming magnet cores whose windings are indicated at 25 and 26. This element carries centrally a solenoid 27 the core of which is indicated at 28. The outer end of the core 28 is recessed at 29 to receive the end of the rivet to be upset, allowing for the desired shape of rivet when finished, and also carries an electrical heating circuit terminal 30 insulated from the core and adapted to engage the end of the rivet. This terminal 30 is also made of copper or other low resistance material, and in this connection it is to be noted that these copper insulated terminals are provided for the purpose of preventing the other portions of the removable elements, such as the retarding bar and the core 28, from heating up to any material degree and thus being deformed. A binding post 31 leads from the terminal 30 through the side of the core 28 and is insulated from the latter, whereby said terminal may be easily connected up in the heating circuit. The engaging ends of the magnet cores 23 and 24 are also provided with feet 32 corresponding in every particular to the feet 20 on the engaging ends of the cores 10 and 11. The windings of the cores 23 and 24 and the solenoid 27 are led through passages 33 and 34 in the arm connecting portion of the element B and are then connected up with suitable switches carried by said element and to be hereinafter referred to. The winding 12 of the dolly bar element is connected to a switch 35 and the latter is connected by conductors 36 with feed line conductors 37 and 38, whereby the magnet formed by the core 10 and winding 12 can be selectively energized or deenergized. The winding 13 of the element A is connected to a switch 39 and the latter is in turn connected to the feed line conductors 37 and 38 by conductors 40 whereby the magnet formed by the core 11 and winding 13 may be selectively energized and deenergized. The terminal 18 is connected by a conductor 41 to one of the conductors 42 of a heating circuit feed line, while the other terminal 30 of the heating circuit is connected by a conductor to a switch 44 carried by the element B and which switch is in turn connected by a conductor 45 to the other conductor 42 of the heating circuit feed line. Preferably I restrict the control of the heating circuit to the workman who is operating the riveting or upsetting element B, but, if desirable, an additional switch could be introduced into this circuit and mounted upon the element A so as to bring the heating circuit within the control of either workman. The winding 25 is connected to a switch 46 and the latter is in turn connected to the feed wires 37 and 38 by conductors 47. The winding 27 of the solenoid is connected to a switch 48 and the latter is in turn connected to the feed wires 37 and 38 by conductors 49. The winding 26 of the core 24 is connected to a reversing switch 50 and the latter is in turn connected to the feed wires 37 and 38 by conductors 51. By introducing the reversing switch 50 into this circuit I am enabled to change the polarity of the magnet formed by the core 24 and winding 26 which change of polarity it is desired to effect just previous to the energization of the solenoid so as to magnetically maintain the elements of the device in proper relation during the upsetting of the rivet. By doing this the magnetic circuit is given a continuous path, with no air gap, said magnetic circuit passing through the solenoid core 28, thus increasing the strength of the solenoid. It is to be noted that the retarding bar or buffer 15, and also the core 28 of the riveting element B, are removably mounted, thus permitting these elements to be replaced by like elements of different design or type according to the class of work being done. This is also of importance in the event of breakage of either one of these elements, as a new one may be readily substituted for a broken or worn-out element. Screw plugs 52 are provided, as shown, to form abutments for the elements 15, 28, and these plugs may be adjusted to suit the type of retarding bar or core being used for the character of the work being done.

In the use of my device only two workmen are necessary, one of whom I will call the "helper" and the other the "riveter." The first step in the operation of riveting together the plates C and D, shown in Figs. 1 to 4, inclusive, is performed by the helper who puts the rivet E in the aligned holes provided in the plates C and D. The helper then places the dolly bar element A in the position shown in Fig. 1 and closes switches 35 and 39 to energize magnets formed by the cores 10 and 11 and the windings 12 and 13 when the magnetic flow will be in the direction indicated by the arrows in Fig. 1. The riveter then puts the upsetting element B in place, as shown in Fig. 2, and closes switches 46 and 50 to produce the magnetic flow shown by the arrows in Fig. 2. The riveter then closes the switch 44 of the heating circuit and heats the rivet E to the required temperature, after which this switch is opened. Following this the riveter operates the switch 50 to reverse the magnetic flow in the core 24, as shown by the arrows in Fig. 3. This reversal of the magnetic flow in the core 24 serves to hold the elements of the device in proper relation and to increase the strength of the solenoid during the upsetting of the rivet E, which is then accomplished by closing the switch 48 to operate the solenoid core 28 as shown in Fig. 4. The operation of riveting is then complete and

the various switches are opened and the elements in the device repositioned for upsetting the next rivet.

It is to be further noted that in the operation of the core 28, said core first tends to move so as to locate itself centrally in the coil of the solenoid 27, and as this force is decreased upon the core nearing the center, the magnetic force of the two magnets, indicated by 23, 24, 25 and 26, come into play as the air-gap is decreased, and thus the final force is across the plate D to the core 28 to close this air-gap. These two forces are employed during the upsetting of the rivet.

15 I claim:—

1. A riveting device comprising a pair of independent magnets, means for energizing and deenergizing said magnets, a rivet holding member carried by one magnet, a rivet upsetting device carried by the other magnet, and heating circuit terminals carried by the rivet holding member and rivet upsetting device respectively and engageable respectively with the ends of a rivet.

2. A riveting device comprising a pair of independent magnets, means for energizing and deenergizing said magnets, a rivet holding member carried by one magnet, a rivet upsetting device carried by the other magnet, a heating circuit, terminals in said circuit carried by the rivet holding member and rivet upsetting device respectively and engageable respectively with the ends of a rivet, and means for opening and closing said circuit.

3. A riveting device comprising a pair of independent magnets, means for energizing and deenergizing said magnets, a rivet holding member carried by one magnet, a rivet upsetting device carried by the other magnet, a heating circuit, terminals in said circuit carried by the rivet holding member and rivet upsetting device respectively and engageable respectively with the ends of a rivet, and means carried by the magnet carrying the rivet upsetting device for opening and closing the heating circuit.

4. In a riveting device, a U-shaped member each leg of which forms a magnet, and engaging feet pivotally connected to the free ends of said leg respectively.

5. In a riveting device, a pair of independent U-shaped members each leg of said members forming a magnet, a rivet holding element carried by one member between its legs, a solenoid carried by the other member between its legs and whose core constitutes a rivet upsetting element, means carried by each member for selectively controlling the energization and deenergization of its associated magnets, means carried by the solenoid carrying member for controlling the energization and deenergization of said solenoid, a heating circuit, terminals in said circuit carried respectively by the rivet hold-

ing element and the solenoid core and engageable with the ends of a rivet respectively, means on the solenoid carrying member for opening and closing the heating circuit, and means on the solenoid carrying member for reversing the direction of magnetic flow of one of its associated magnets.

6. In a riveting device, a U-shaped member each leg of which forms a magnet, means for selectively controlling the energization and deenergization of said magnets, a solenoid carried by said member between its legs, and whose core constitutes a rivet upsetting element, means for controlling the energization and deenergization of said solenoid, and means for reversing the magnetic flow of one of the magnets.

7. A riveting device comprising a pair of independent magnets, means for energizing and deenergizing said magnets, a removable rivet holding member carried by one magnet, and a removable rivet upsetting device carried by the other magnet.

8. A riveting device comprising a pair of independent magnets, means for energizing and deenergizing said magnets, a rivet holding member carried by one magnet, a rivet upsetting device carried by the other magnet, and adjustable abutments for said holding member and upsetting device.

9. In a riveting device, a U-shaped member each leg of which forms a magnet, means for selectively controlling the energization and deenergization of said magnets, a solenoid carried by said member, and whose core constitutes a rivet upsetting element, means for controlling the energization and deenergization of said solenoid, and means for reversing the magnetic flow of one of the magnets thereby permitting the magnetic circuit to pass through the solenoid core and thus increase the strength of said solenoid during its upsetting operation.

10. A riveting device comprising a pair of independent magnets, means for energizing and deenergizing said magnets, a rivet holding member carried by one magnet, a rivet upsetting device carried by the other magnet, a heating circuit, low resistance terminals for said circuit carried by the rivet holding member and rivet upsetting device respectively and insulated therefrom, said terminals engageable respectively with the end of a rivet, and means for opening and closing said circuit.

11. A riveting device comprising a pair of independent magnets, means for energizing and deenergizing said magnets, a rivet holding member carried by one magnet, a rivet upsetting device carried by the other magnet, and means associated with one of the magnets for increasing the force of the upsetting device.

12. A riveting device comprising a pair of independent magnets, means for ener-

gizing and deenergizing said magnets, a rivet holding member carried by one magnet, an electro-magnetic upsetting device carried by the other magnet, and means associated with the magnet carrying the rivet upsetting device for increasing the force of said upsetting device.

13. A riveting device comprising a pair of independent magnets each having a plurality of coils, a rivet holding member carried by one magnet, an electro-magnetically operated rivet upsetting device carried by the other magnet, and means associated with one coil of the magnet carrying the rivet upsetting device for reversing the polarity through the coil whereby the magnetic force through the rivet upsetting device is increased.

14. In a riveting device, a U-shaped member each leg of which forms a magnet, a

rivet holding device carried by the member between the legs, and means carried by the member for selectively controlling the energization and deenergization of the magnets.

15. In a riveting device, a U-shaped member each leg of which forms a magnet, means for selectively controlling the energization and deenergization of said magnets, a solenoid carried by said member between its legs, and whose core constitutes a rivet upsetting element, and means for controlling the energization and deenergization of said solenoid.

In testimony whereof I affix my signature in presence of two witnesses.
